(57) **CLAIM**

The ornamental design for a clip for a headset, as shown and described.

DESCRIPTION

FIG. 1 is a perspective view of a clip for a headset showing our new design;

FIG. 2 is a front perspective view thereof; and,

FIG. 3 is a rear perspective view thereof.

The broken line showing environmental structure is for illustrative purposes only and forms no part of the claimed design.

1 Claim, 3 Drawing Sheets

FIG. 1

FIG. 2

FIG. 3
